UNITED STATES PATENT OFFICE.

WILLIAM A. UNDERWOOD, OF WORCESTER, AND JOHN ZIMMERMAN, OF AUBURN,
MASSACHUSETTS.

CALENDER-ROLL GRINDER.

1,285,476.

Specification of Letters Patent. Patented Nov. 19, 1918.

Application filed January 26, 1918. Serial No. 213,852.

To all whom it may concern:

Be it known that we, WILLIAM A. UNDERWOOD and JOHN ZIMMERMAN, citizens of the United States, residing at Worcester and 5 Auburn, respectively, in the county of Worcester and State of Massachusetts, have invented a new and useful Calender-Roll Grinder, of which the following is a specification.

10 This invention relates to an improvement in traverse grinding devices for calender rolls of the type represented in our Patent No. 1,255,360, granted February 5, 1918, on the copending application Serial

15 No. 157,038 filed March 23, 1917. The objects of this invention are the same as the objects of that one and also to provide simple and convenient means for adjusting the bed or frame of the grinding device

20 vertically, longitudinally and laterally, and effective means for supporting the same and permitting of these adjustments and clamping it in its adjusted positions. This case also includes one form of the invention

25 shown in our above identified application but not specifically claimed therein and is, to that extent only a division thereof. Other objects and advantages of the invention will appear hereinafter.

30 Reference is to be had to the accompanying drawings in which—

Figure 1 is an end elevation of a calender with a preferred embodiment of this invention applied thereto;

35 Fig. 2 is an enlarged side elevation of the grinding device;

Fig. 3 is a rear view;

Fig. 4 is a plan of the supporting slide only;

40 Fig. 5 is a rear elevation of a modification constituting matter divided out of our above identified application;

Fig. 6 is a side view of the same, and

45 Fig. 7 is a sectional view on the line 7—7 of Fig. 5.

As in our first application above identified the invention is shown as applied to a calender having frame ends A and calender rolls B to be ground. The frame is provided with a series of bolt holes on its two opposite ends and two brackets 10 are bolted thereto and leveled so as to support the apparatus.

The two brackets are provided with a

cross bar 11 at the center of which is placed 55 a large vertical adjusting screw 12 for regulating the elevation of the device and constituting a support for the whole grinding mechanism. This screw is provided with a spherical seat 13 for receiving a spherical 60 bottom 14 on a base 15. The bolt 12 is provided with a conical passage 16 extending down through from the spherical seat and larger at the bottom than at the top. Through this passes a bolt 17 having a head 17^a setting in 65 a recess in the base 15. The bottom of the adjusting screw 12 is also provided with a spherical end and the bolt 17 has a washer 18 having a spherical seat at the top fitting this end and held against it by a nut. This 70 bolt and nut are used for clamping the parts in adjusted positions.

It will be understood that the base 15 can be turned either sidewise or longitudinally and twisted or tilted in any desired direction 75 within certain limits in its spherical seat 14 and that the bolt and nut will clamp it in its adjusted position.

In addition to this the base 15 is provided with longitudinal ways which support 80 a slide 20 adapted to be moved back and forth along said ways by an adjusting screw 21. A clamping bolt 22 is provided for holding this slide when once adjusted. This slide is provided with undercut ends 23 for 85 receiving projections on the grinder bed or frame 24 and with a bolt 25 for clamping the same on the slide. This grinder bed is the same as the so-called frame 12 in our above identified application and carries the 90 grinding mechanism comprising a feed screw 26, nut 27 operating handle 28, motor 29, grinding wheel shaft 30, and grinding wheel 31. Any of the other associated parts illustrated in that application can be employed in connection with these if desired. In this way it will be seen that in addition to the advantages set forth in our prior application universal adjustment of the grinding wheel can be secured and the parts fixed 95 in adjusted position.

In the form shown in the last three figures, the device is mounted in any desired way but the frame 24 is provided with end uprights 42 which support a driving shaft 43. This 105 driving shaft is operated from an external source of power by a belt on a pulley 44, thus eliminating the motor shown in the

other figures. The frame 24 is provided with the screw 26 shown in the other figures, and connected in the same way with a slide 45 traveling on ways on the frame 24.

5 This slide is provided with a pulley 46 which slides with it and is adapted to engage two intermittent keys 47 on opposite sides of the shaft 43 so that it will rotate with that shaft in all positions of the slide. Pivotally mounted on this slide concentric with the shaft 43 is a frame 48 having an inwardly extending arm 49 bolted thereto. The slide is provided with a rotary worm 50 operated by a handle 51 and meshing with a 15 segmental worm gear 52 fixed on the frame 48. By turning this worm 50 therefore, the arm 49 can be raised and lowered about the center of the shaft 43 as a pivot.

The pulley 46 is adapted to transmit 20 power by a belt to a pulley 53 on a shaft 54 carried by the arm 49 and carrying the grinding wheel 31. This device operates in a manner substantially the same as the other except that the power for driving the wheel 25 is derived through the shaft 43 from an external source and the arm 49 can be set at different angles so as to grind two calender rolls from one position of frame 24.

Although we have illustrated and 30 described only two forms of the invention we are aware of the fact that other modifications can be made therein without departing from the scope of the invention as expressed in the claims. Therefore we do not wish to 35 be limited to all the details of construction herein shown and described, but what we do claim is:—

1. In a portable calender roll grinder, the combination of a support, a base mounted 40 on said support and capable of being twisted sidewise and tilted thereon, means for clamping the base with respect to said support after adjustment, a grinding bed or frame carried by said base and provided with a 45 grinding wheel, and means for operating said wheel in its adjusted positions.

2. In a portable calender roll grinder, the combination of a support adapted to be applied directly to the end housings of the calender at different elevations, a grinding bed or frame carried by said support and adjustable vertically thereon and also adjustable about a pivot sidewise and longitudinally, an arm carried by said bed and adapted to 55 project in between the housings of the calender frame, a shaft located at each end of said arm, a grinding wheel on one shaft, means for driving the other shaft and for transmitting the rotation to the grinding wheel 60 shaft, a screw carried by said bed and con-

nected with the arm, and means for rotating said screw to move the arm back and forth.

3. In a portable calender roll grinder, the combination of a support, a vertical screw carried by said support having a spherical 65 seat at the top, a base having a portion fitting in said spherical seat and capable of twisting and tilting thereon, means extending through said screw for holding the base in its adjusted positions, and a grinding bed 70 carried by said base.

4. In a portable calender roll grinder, the combination of a support, a vertical screw carried by said support having a spherical seat at the top, a base having a portion fitting in said spherical seat and capable of twisting and tilting thereon, means extending through said screw for holding the base in its adjusted positions, and a grinding bed 75 carried by said base and longitudinally adjustable thereon.

5. In a portable calender roll grinder, the combination of a support adapted to be applied to the housings of a calender, a grinder bed carried by said support, an arm carried 85 by said bed, a grinding wheel on the arm, means supported by the bed for rotating the wheel, and means for adjusting said arm to swing about an axis parallel with the axis of the grinding wheel.

6. In a portable calender roll grinder, the combination of a support adapted to be applied directly to the end housings of the calender at different elevations, a grinding bed or frame carried by said support and 95 adjustable vertically thereon and also adjustable about a pivot sidewise and longitudinally, an arm carried by said bed and adapted to project in between the housings of the calender frame, a shaft located at 100 each end of said arm, a grinding wheel on one shaft, and means for driving the other shaft and for transmitting the rotation to the grinding wheel shaft.

7. In a portable calender roll grinder, the combination of a support adapted to be applied directly to the end housings of the calender at different elevations, a grinding bed or frame carried by said support and adjustable about a pivot sidewise, an arm carried by said bed and adapted to project in 105 between the housings of the calender frame, a shaft located at each end of said arm, a grinding wheel on one shaft, and means for driving the other shaft and for transmitting 110 the rotation to the grinding wheel shaft.

In testimony whereof we have hereunto affixed our signatures.

WILLIAM A. UNDERWOOD.
JOHN ZIMMERMAN.
